UNITED STATES PATENT OFFICE

DAVID JACOB HYNEMAN AND IRVEN WASHINGTON HYNEMAN, OF CORINTH,
MISSISSIPPI.

HAY-PRESS.

SPECIFICATION forming part of Letters Patent No. 377,458, dated February 7, 1888.

Application filed October 25, 1887. Serial No. 253,343. (No model.)

To all whom it may concern:

Be it known that we, DAVID JACOB HYNEMAN and IRVEN WASHINGTON HYNEMAN, residents of Corinth, in the county of Alcorn and 5 State of Mississippi, have invented certain new and useful Improvements in Hay-Presses; and we do hereby declare the following to be a full, clear, and exact description of the invention, such as will enable others skilled in the art to 10 to which it pertains to make and use the same.

Our invention relates to improvements in portable hay-presses of the class in which the press proper is mounted on wheels and is adapted to be moved from place to place in 15 a field and operated at any point or any number of points therein.

The invention is fully described and explained in this specification, and shown in the accompanying drawings, in which—

20 Figure 1 is a side elevation of a press of our improved construction, a number of the parts of the frame being broken away to show the internal construction. Fig. 2 is a top plan of the machine; and Fig. 3 is a side elevation of 25 the rear portion of the wheeled support of the press, together with the press proper, the latter being in the vertical position in which it is placed for filling.

20 In the views, A is a wagon bed or frame, of any known or desired construction, supported by front and rear wheels, A' A", mounted on suitable axles. A stationary frame or platform, B, is rigidly mounted on the front end of the wagon-bed, and is provided at its rear 35 end with a vertical platen or press-bed, B', in whose rear face are formed horizontal grooves or gains b for the insertion of binding-wires. A vertical capstan or windlass, C, is journaled in suitable bearings in the front end of the 40 stationary frame B, and is provided with an operating sweep or lever, C', or any other means for its convenient rotation.

On the rear portion of the wagon-bed is a press-chamber, D, provided with a horizontal 45 shaft, d, which is journaled in suitable bearings fastened to the wagon-bed immediately over the rear axles, and to the front end of the press-chamber D, and between it and the platen B', is fastened, by means of hinges d', 50 a cap or hood, D', which forms a continuation of the press-chamber, and is provided with

latches L, pivoted to its opposite vertical faces and adapted to engage catches L' in the wagon-bed, the object of these latches and the catches with which they engage being to fasten the hood 55 to the wagon-bed or to release it when desired. The press chamber D is provided with a follow-board, E, lying and adapted to slide freely within it, and formed in its front face with horizontal grooves or gains e', corresponding in 60 position to the similar grooves, b, in the platen B'. The follow-board E is provided with arms or lugs e, projecting from its opposite vertical edges, and these arms rest and slide freely in longitudinal grooves in the vertical faces of the 65 press-chamber. A rope, F, passes through the capstan C, and thence about pulleys G, mounted on pivots which are fastened to suitable supports, g, and is carried thence to the rear of the press-chamber, where its ends are looped 70 about the arms or lugs e, as illustrated in Fig. 1.

The rope may be securely fastened at the point where it passes through the capstan C; but we prefer to have it slip loosely through the hole in the capstan, in order that when the 75 capstan is rotated the resistance may equalize the length of the parts of the rope lying between the capstan and the respective arms e.

It is evident that if in any manner the press-chamber be filled with hay or other substance 80 susceptible of compression and the ends of the rope F be looped about the arms e of the follow-board E, the rotation of the capstan will wind the rope about it and draw the follow-board forward in the chamber, thus compressing 85 the hay or other material therein.

In operation the entire machine is movable from place to place, and when so in motion its parts are preferably in the positions illustrated in Fig. 1, the press-chamber being horizontal and the hood D being swung downward upon the wagon-bed and secured by means of the latches L and catches L'. When the machine reaches the place at which it is desired to bale hay or other material the latches L 95 are released from the corresponding catches and the entire press and hood are swung into the vertical position indicated in full lines in Fig. 3, the hood being swung back, if desired, to the position illustrated in dotted lines in 100 said figure, and the follow-board E being at the rear or bottom end of the press-chamber.

In this position the press-chamber may be readily filled with hay, cotton, or other compressible material, and when so filled the rear end of the press-chamber is swung upward 5 until the chamber and its hood reach the position shown in full lines in Fig. 1, when the hood is fastened down by means of the latches L. The follow-board is now drawn forward by means of the rotation of the windlass or 10 capstan C and the winding of the rope about it until the lugs or ears e reach the front ends of the longitudinal slots in the sides of the press-chamber, the follow-board then being in the position indicated at E', Fig. 1, and the 15 compressed material being between the follow-board and the platen B'. The latches L are then released from the catches L' and the hood D' is swung upward to the position indicated in dotted lines in Fig. 1, when the 20 pressed material between the follow-board and the platen is readily accessible. Binding-wires are then inserted in the grooves or gains in the platen and follow-board and are fastened about the bale of compressed material, which 25 may then be readily released from its position, thus preparing the machine for a second operation.

In order that the hood D' may swing upward when desired in the manner described, the 30 side pieces, D'', of the hood are placed in vertical planes wholly outside of the extreme limits of the platen B', and slots or recesses B'' are formed in the front edge of the stationary platform B, as indicated in Figs. 1 and 2, for the 35 purpose of allowing the free passage of the lower front corner of each of the side boards, D'', of the hood.

Having now described and explained our invention, what we claim as new, and desire to 40 secure by Letters Patent, is—

1. In a press of the class described, the combination, with a suitable bed and its supporting-wheels, of a stationary frame or platform mounted on the front end of said bed, a wind-

lass or capstan journaled therein and provided 45 with means for its rotation, a press-chamber supported by a transverse pivot journaled in suitable bearings at the rear end of the wagon-bed, and a swinging hood hinged to the front end of the press-chamber and forming a continuation thereof, and lying between it and the rear face of said stationary platform, substantially 50 as and for the purpose set forth.

2. The combination, with the bed A and its supporting-wheels A' A'', of the stationary 55 platform B, mounted on the front end of said bed, the windlass C, journaled in said stationary platform, the press-chamber D, mounted on a horizontal shaft journaled in bearings on the rear end of the bed, and the hood D', 60 hinged to the front end of the press-chamber and provided with means for locking it to the bed or an attachment thereof, substantially as shown and described, the rear edge of the stationary platform being formed with slots B'', 65 permitting the upward swing of the hood, substantially as and for the purpose set forth.

3. The combination, with the wagon-bed A and its supporting-wheels A' A'', of the platform B, having at its rear end the platen B', 70 formed with grooves b, the press-chamber D, pivotally mounted on the rear end of the bed, the follow-board E, lying within the press-chamber and having grooves e' in its front face, the hood D', hinged to the press-chamber and 75 lying between it and the platen B', and means, substantially as shown and described, for drawing the follow-board forward in the press-chamber, substantially as and for the purpose set forth.

In testimony whereof we have signed this specification in the presence of two subscribing witnesses.

DAVID JACOB HYNEMAN.
IRVEN WASHINGTON HYNEMAN.
